UNITED STATES PATENT OFFICE.

THOMAS F. LUNDERGAN, OF MARION, OHIO.

CULVERT.

1,165,425.

Specification of Letters Patent. Patented Dec. 28, 1915.

Application filed March 30, 1914. Serial No. 828,307.

To all whom it may concern:

Be it known that I, THOMAS F. LUNDERGAN, a citizen of the United States, residing at Marion, in the county of Marion, State of Ohio, have invented certain new and useful Improvements in Culverts; and I do hereby declare the following to be a full, clear, and exact description of the invention, such as will enable others skilled in the art to which it appertains to make and use the same.

This invention relates to new and useful improvements in metallic culverts and more particularly to that class of culverts built up of a plurality of separable sections.

The object of the present invention resides in the provision of a culvert composed of a plurality of sections which may be readily assembled to provide a strong and compact structure without the use of any securing means such as nuts or bolts, and to this end the invention resides in the provision of a culvert including a bottom and sides so connected to the bottom that they cannot move laterally or vertically with relation thereto.

A further object of the invention resides in the provision of such a culvert which may be very easily assembled or disassembled as desired and which comprises a minimum number of parts so that it may be manufactured at a comparatively low cost.

With these and other objects in view, the invention resides in the novel combination, formation and arrangement of parts to be more fully hereinafter described and illustrated in the accompanying drawings and particularly pointed out in the claims here-to appended.

Reference is had to the accompanying drawings wherein similar characters of reference designate corresponding parts throughout the several views, and in which:

Figure 1 is a perspective view of a portion of a culvert constructed in accordance with the present invention, Fig. 2 is a vertical transverse sectional view through the structure shown in Fig. 1, Fig. 3 is a perspective view of one of the side plates of the culvert and Fig. 4 is a perspective view of a modified form of base plate, and Fig. 5 is a section on the line 5—5 of Fig. 2. Fig. 6 is a fragmentary sectional view taken transversely through the side members.

Referring now more particularly to the accompanying drawings, the culvert com-

prises a plurality of base plates 5, of substantially oblong shape and having their ends abutting. Side members 7 and 8 are provided and are each arcuate in cross section and have their tops meeting to form with the base members, an inclosed passage-way.

To provide means for detachably securing the side members to the base members, said base members have extended outwardly from their side edges, spaced tongues 9 which have the outer portions of their bottom faces downwardly beveled as at 11. Each of the side members has a tongue or a plurality of tongues 12 adapted to seat in the space between the tongues 9 of the adjacent base member, and the lower portion of the tongues 12 are provided at each end with outwardly extending lugs 13 engaging the bottom face of the tongues 9. To assemble the members, the side members are placed with their tongues disposed adjacent and under the tongues 9 of the base member and they are then rocked with the bottom faces of the tongues 9 as a fulcrum to position the tongues 12 between the tongues 9. In this position the side members are held against vertical movement by the lugs 13 and against outward horizontal movement by the beveled portions 11 of the tongues 9. The lower edge of the inner face of the side members is formed with a longitudinal rib 14 engaging the face of the base plate to prevent the side members from rocking inwardly too far.

To provide a union for the meeting top edges of the side members, the member 7 is formed with a laterally extending portion 15 at its upper edge, and disposed on the inner face of the member are pairs of lugs 16 which extend substantially parallel to the portion 15, the end of the member 8 seating between the lugs and the portion 15, and being provided with lugs 15' which seat between respective lugs 16.

In Fig. 4 is shown a slight modification, wherein the sides of the base plate are upwardly offset at 17 to facilitate the assembling of the culvert.

From the foregoing it is observed that a structure has been provided wherein the side members of the culvert are held against displacement vertically and against displacement laterally without first swinging said side members with their base edges as fulcrums.

What is claimed is:

A culvert comprising a base member, spaced tongues extending outwardly from the side edges of the base member and having their bottom faces downwardly beveled, side members adapted to mutually engage at their upper portions, tongues on the bottom edges of the side members disposed between tongues of the base member

and lateral extensions at the lower portions of the second-named tongue engaging the bottom faces of the first-named tongue.

In testimony whereof I affix my signature, in the presence of two witnesses,

THOMAS F. LUNDERGAN.
